(Cl. D34—4)

FIG. 1

FIG. 2

FIG. 3

FIG. 4

FIGURE 1 is a front elevational view of a doll showing one embodiment of my design;

FIG. 2 is a side elevational view of the head of the doll taken as indicated by line 2—2 of FIG. 1;

FIG. 3 is a front elevational view of a doll showing a second embodiment of my design; and

FIG. 4 is a side elevational view of the head of the doll taken as indicated by line 4—4 of FIG. 3.

The dominant features of my design consist in the doll head shown herein in full lines having a flat back, jutting jaw, button nose, and facial features all as shown.

This application is a continuation of my design applications Serial Numbers D-59,051 and D-59,052, filed January 15, 1960 and now abandoned.

I claim:

The ornamental design for a doll, as shown and described.
